ELEVATOR AND LATCH CONSTRUCTION

Herbert E. Grau, Los Angeles, Calif., assignor to
Byron-Jackson Co., Los Angeles, Calif., a cor-
poration of Delaware

Application September 16, 1935, Serial No. 40,745

12 Claims. (Cl. 24—248)

This invention relates to elevators for raising and lowering pipe into and out of a well, such as an oil well. More particularly, the invention relates to elevators for use with so-called "external upset pipe".

The pipe ordinarily consists of sections of pipe joined together with couplings, collars or tool joints having a larger outside diameter than the pipe and having a flat annular shoulder on the lower end of each coupling, collar or tool joint. The elevators commonly used with such pipe are known as "collar type elevators". Collar type elevators have a pair of hinged members adapted to encircle the pipe, and provided on the upper side with an annular flat bearing surface adapted to support the said flat annular shoulder at the coupling or joint to enable the pipe to be raised or lowered by the elevator and its associated hoisting mechanism.

"Collar type elevators" are usually of either one of two types, commonly called "center latch" or "side door" elevators. A center latch elevator comprises two semi-circular pipe engaging members jointed together at one end, preferably by a hinge connection, and adapted to be latched around a pipe. In this case the latch is at the front or "center" of the elevator, whereas in a side door elevator the latch would be located at one side of the elevator.

So-called "external upset" pipe does not have flat, annular shoulders and therefore cannot be handled by ordinary collar type elevators. External upset pipe is formed with upset ends forming enlarged portions, the outer walls of which are flared upwardly; that is to say, the outer face is inclined or tapered gradually outwardly and upwardly at an angle of about 18° from the axis of the pipe. External upset pipe has heretofore been handled by the use of lifting plugs or slip-type elevators, both of which are objectionable. The plug method is cumbersome and expensive because a plug must be screwed into the upper end of each stand of pipe as it is pulled from the well and must be removed when the pipe is run back into the well. The use of slip type elevators is objectionable because such elevators are of necessity quite large and heavy and are hard to handle.

An object of the present invention is to provide an elevator capable of handling external upset pipe without the use of plugs or slips.

On account of the enormous weight of a tube string and the "wedge" form at the upset, an extraordinary spreading stress is developed in the elevator tending to swing it open, and one of

the objects of this invention is to provide a center latch elevator for handling external upset pipe, in which the elevator has a latch construction capable of withstanding these spreading strains.

Another object is to provide a secondary latching means to prevent accidental opening of the principal latch means, as might occur, for example, from a downward blow caused by the upset portion of the pipe striking downwardly into the elevator bore.

Another object is to provide a construction whereby, in an elevator with a hinged latch, the latch hinge pin is relieved of all strain.

In the drawings:

Figure 1 is a plan of an elevator embodying my invention, with parts broken away at the front and shown in section to illustrate details of the latch and lock;

Figure 2 is a front elevation of the elevator 20 illustrated in Fig. 1;

Figure 3 is a side elevation and partial section about on the line III—III of Fig. 1; and

Figure 4 is a detail on a larger scale and is a horizontal section about on the line IV—IV 25 taken through the latch and lock at the front and with the elevator in a partially open position.

In accordance with my invention, I provide a releasable latch that holds the elevator closed 30 at the front. This latch is pivoted at one side and its free end engages over a lug at the opposite side to hold the elevator closed.

I prefer to construct the parts so that the pivot pin is relieved of strain when tensile stresses are 35 developed in the latch. For this purpose the part on which the latch is pivoted is provided with means for engaging the latch and the pivot connection of the latch is made loose so as to permit this.

The latch is preferably provided with a lock mounted in such a way that the stresses in the latch do not resist the opening of the latch. For this purpose the lock is mounted so that the direction of its initial movement in opening, is substantially at right angles to the direction of the latch, and the lock is provided with a handle and a construction such that when the lock is operated to release the latch, the lock handle then 50 serves as the latch handle so that continued movement will release the latch. Although my improvements may be applied to other types of elevators, in the present specification they are described as applied to an elevator of center latch 55

type, and which is constructed to handle upset pipe.

Referring more particularly to the parts, 1 and 2 indicate two substantially semi-circular collar sections, encircling the pipe, said members having adjacent faces that come together to form a bore 3 to receive the pipe.

The members 1 and 2 are connected together at one end by a joint preferably including a hinge-pin 4.

The elevator is provided with suitable means, such as the lugs 5, for hanging it on bails or elevator links, not illustrated.

The latch 6 is preferably of bifurcated form with substantially horizontal bars 7 connected by integral vertical bars 8 and 9. In the closed position of the latch the outer bar 9 fits over a latching lug 10 that projects outwardly from the free end of the member 2, and the engaging faces 11 on the lug 10 and 12 on the bar 9 are struck on a radius from the axis of the latch bolt 13 as a center, and furthermore, these faces 11 and 12 though slightly curved extend in a direction substantially at right angles to the direction of initial movement of the free ends 14 of the member 2 when it swings open. And in order to hold the latch closed, I prefer to provide a lock 15 movably mounted on the latch and provided with an operating handle to release it; the further movement of this handle operating to open the latch.

The lock is preferably loose on a long pin 16 secured in the latch and provided with a coil spring 17 that urges the lock in a direction to keep its hook end or hook 18 in engagement with a part on the elevator. The hook preferably engages into a socket 19 having a shoulder 20 extending substantially at right angles into the face 11. The lock 15 swings in a recess 21 formed in the vertical bar 9, and is provided with an operating handle in the form of a vertical bar 22.

The lock construction also includes a stop 23 which may be formed as a lug projecting from the lower portion of the lock and this stop is adapted to strike against the corresponding stop 24 formed on the lower horizontal bar of the latch. The engagement of these stops 23 and 24 limits the swing of the lock in the opening direction and permits sufficient movement of the hook 18 to disengage it from the shoulder 20. A continued pull upon the handle 22 will then swing the latch outwardly on its pivot pin 13 and release the latch.

The latch is normally urged toward its closing position by suitable resilient means, preferably in the form of a coil spring 25 (see Fig. 1) that is mounted in a spring chamber 26 in the pipe encircling member 1, the outer end of the spring thrusting against a short arm 27 that projects inwardly from the latch at its pivoted end.

In addition to the stop 23 the lock is further provided with a second stop 28 in the form of a lug or finger that projects inwardly from the axis of rotation of the lock and this stop 28 cooperates with a stop shoulder 29 formed at one side of the stop 24 (see Fig. 4). This stop 29 limits the swinging movement of the lock in its locking direction under the action of its spring 17 and when the latch is in its open position it holds an inclined edge 30 of the hook 18 in a position to strike the corner 31 of the latching lug 10, and this inclined edge 30 causes a cam action to push back the hook 18 and enable it to snap into the hook socket 19.

When a pipe string is being supported in the elevator it will be evident that the tapered upset portion of the pipe seating on the conical seat 3a exerts a considerable force tending to spread the members 1 and 2 in the direction to open the elevator. This spreading force is of course resisted by the latch and in an ordinary latch construction would subject the latch-pin 13 to a considerable shearing strain. In order to relieve the pin 13 of such a shearing stress, I prefer to have the latch mounted loosely on the pin 13. That is to say, the pin 13 has what is commonly called, a "sloppy" fit in the latch, and I provide the free end 32 of the pipe inserting member 1 with a latching lug 33 which is disposed opposite to the latching lug 10 and the outer face 34 of this latching lug is preferably of concave curved form so as to fit closely to the side of the vertical bore 8 of the latch which is correspondingly curved. With this construction it will be evident that when the latch is in its closed position the latch will bear against the face 11 and against the curved face 34 of the lug 33 so that the spreading forces acting in a horizontal plane and exerted by the elevator on the latch will be directly resisted by tensile forces developed in the latch itself without straining the pin 13.

In order to relieve the latch of any shearing stresses or other stresses acting in a more or less vertical plane, I prefer to form an interlocking connection between the two sections of the elevator as illustrated in Fig. 2 by providing a substantially horizontal tongue 35 which projects into a corresponding socket 36 formed in the adjacent meeting face of the member 2.

In order to facilitate opening and closing of the elevator, the free ends of the elevator sections 1 and 2 are provided with forwardly projecting inclined horns or handles 37 that terminate in the ball handle 38.

The lugs 5 may be formed with an upper fork 5a and a lower fork 5b connected by a locking bar 39 to prevent dislodgment of the elevator links from the lugs and to enable the stresses developed in the upper fork to be imparted through the locking bars 39 through the lower fork 5b. This construction is covered, however, in a co-pending application Serial No. 741,249, filed August 24, 1934, by Chester L. Lundeen.

The elevator preferably has a cylindrical bore 3b above the tapered seat 3a, and this bore 3b is larger than the diameter of the pipe supported in the elevator.

One of the advantages arising from having the tapered seat of the elevator depressed, that is, located considerably below the upper face of the elevator, and the enlarged bore 3b above the seat, is that the stresses developed by the load, lie in a horizontal plane well within the body of the elevator. This brings more metal into the stressed zone and greatly increases the strength of the structure. This location for the seat also increases the stability of the loaded elevator and reduces the tendency of the elevator to tip.

It is understood that the embodiment of the invention described herein is only one of the many embodiments this invention may take, and I do not wish to be limited in the practice of the invention, or in the claims, to the particular embodiment set forth.

What I claim is:-

1. A well pipe elevator for use with external upset pipe comprising a pair of substantially similar pipe encircling members having a joint connecting the same together at their rear ends and

at the back of the elevator, said members adapted to close together around the pipe, and having adjacent faces cooperating to form a bore with a downwardly and inwardly tapered seat 5 conforming substantially to the tapered portion of the upset pipe, whereby said tapered seat supports the pipe, and the weight of the pipe against the tapered seat tends to force the pipe encircling members apart; and releasable pivoted latch 10 means at the front of the elevator opposite the said joint, and at the free ends of said members for holding said members in place around the pipe.

2. A well pipe elevator for use with external 15 upset pipe comprising a pair of pipe encircling members having a joint connecting the same together at one end, and adapted to swing in the same plane so as to close together around the pipe, said members having adjacent faces 20 cooperating to form a bore with a downwardly and inwardly tapered seat conforming substantially to the tapered portion of the upset pipe, whereby said tapered seat supports the pipe, and the weight of the pipe against the tapered seat tends 25 to force the pipe encircling members apart, a releasable latch member for latching the free ends of the elevator around the pipe, a spring normally urging said latch member to the latched 30 position, a releasable locking member for locking the latch in the closed position, and a spring normally urging said locking member to the locked 35 position.

3. An elevator as described in claim 2 in which the latch member is pivoted to one of the pipe 40 encircling members so as to swing in a horizontal plane, a lug on the free end of the other pipe encircling member adapted to engage the latch, the locking member being pivoted to the latch member to swing in a horizontal plane, and adapted to engage said lug in such a manner 45 that the direction of the initial opening movement of the locking member is at substantially a right angle to the direction of the initial opening movement of the latching face of the latch member.

4. A well pipe elevator for use with external 50 upset pipe comprising a pair of substantially semi-circular pipe encircling members hinged together at one end and having adjacent faces 55 cooperating around a pipe to form a pipe-receiving bore, said bore having an annular, downwardly and inwardly tapered seat conforming substantially to the tapered upset portion of the pipe, latch means pivotally connected to one of said pipe-encircling members to swing in a horizontal plane, a movable lock for said latch mounted near the free end of the latch to move 60 in a horizontal plane, the direction of the initial opening movement of the lock and the latch being substantially at right angles to each other, said latch and lock having means to engage the other pipe-encircling member to lock the encircling members together, a handle for said lock, said latch mounted so that the initial opening movement 65 of the handle disengages the lock and the continued movement of said handle disengages and opens said latch.

5. A well pipe elevator for use with external 70 upset pipe comprising a pair of pipe encircling members having a joint connecting the same together at one end, and adapted to close together around the pipe, said members having adjacent faces 75 cooperating to form a bore with a downwardly and inwardly tapered seat conforming substantially to the tapered portion of the up-

set pipe, whereby said tapered seat supports the pipe, and the weight of the pipe against the tapered seat tends to force the pipe encircling members apart, a latch having a loose pivot connection with one of the pipe-encircling members near the free end thereof, said pipe-encircling members each having a lug for engaging the latch, said latch and said lugs cooperating in the closed position of the latch, to secure the pipe encircling members in their closed position, said loose pivot connection operating to relieve the pivot connection of stresses and enabling the lugs to develop tension in the latch while the same is holding the elevator closed.

6. A well pipe elevator for use with external 15 upset pipe constructed so as to open on its forward side to receive the pipe, and having a bore 20 conforming substantially to the shape of the upset portion of the pipe so as to form a seat for the same and support the pipe, a latch for securing the elevator in its closed position, a loose 25 pivot connection for the latch on one side of the elevator at the front, each side of the elevator at the front having means for engaging the latch in its closed position, said loose pivot connection enabling the sides of the elevator to impart tensile stress to the latch while the same is holding the elevator closed.

7. A well pipe elevator for use with external 30 upset pipe constructed so as to open on its forward side to receive the pipe, and having a bore 35 conforming substantially to the shape of the upset portion of the pipe so as to form a seat for the same and support the pipe, a latch for securing the elevator in its closed position, a loose 40 pivot connection for the latch on one side of the elevator at the front, each side of the elevator at the front having a lug for engaging the latch, said loose connection enabling the lugs to impart a tensile stress to the latch in the closed position of the elevator and relieve the pivot connection of strain.

8. A well pipe elevator for use with external 45 upset pipe constructed so as to open on its forward side to receive the pipe, and having a bore 50 conforming substantially to the shape of the upset portion of the pipe so as to form a seat for the same and support the pipe, a latch for securing the elevator in its closed position, a loose 55 pivot connection for the latch on one side of the elevator at the front, each side of the elevator at the front having means for engaging the latch in its closed position, said latch being of bifurcated form with lug-engaging ends, the free ends of said pipe-encircling members having lugs for engaging the ends of the latch, said loose 60 pivot connection enabling the lugs to develop tensile stress in the latch in the closed position of the elevator.

9. A well pipe elevator for use with external 65 upset pipe constructed so as to open on its forward side to receive the pipe, and having a bore 70 conforming substantially to the shape of the upset portion of the pipe so as to form a seat for the same and support the pipe, a latch for securing the elevator in its closed position, a loose 75 pivot connection for the latch on one side of the elevator at the front, each side of the elevator at the front having means for engaging the latch in its closed position, said latch being of bifurcated form, with a pair of substantially horizontal bars and with substantially vertical end bars, the free end of each of said pipe-encircling members having a lug for engaging its adjacent end bar, said loose connection enabling

both of said lugs to engage the latch ends and develop tensile stress in the same, when the elevator is closed and relieving the pivot of stress.

10. A well pipe elevator for use with external upset pipe comprising a pair of pipe encircling members having a joint connecting the same together at one end, and adapted to close together around the pipe, said members having adjacent faces cooperating to form a bore with a downwardly and inwardly tapered seat conforming substantially to the tapered portion of the upset pipe, whereby said tapered seat supports the pipe, and the weight of the pipe against the tapered seat tends to force the pipe encircling members apart; a latch pivotally mounted on the free end of one of said pipe-encircling members, the opposite pipe-encircling member having a lug with an engaging face for cooperating with the latch, said engaging face extending in a direction substantially at right angles to the direction of initial movement of the said free ends when the same swing apart to open the elevator, a lock pivotally mounted on the latch having a hook; the encircling member with the lug also having means for engaging the hook, the said lock being mounted on its pivot so that the initial movement of said hook is in a direction substantially at right angles to the engaging face of the lug, said lock having an operating handle, and said parts cooperating so that when

the handle is pulled the lock can be withdrawn by the first part of its movement, and the latch withdrawn by the latter part of its movement.

11. An elevator for supporting tapered upset tubing, having two doors hinged together and having a tapered seat depressed considerably below the upper face of the elevator for supporting the tapered upset of the tubing, and a latch connecting the two doors for holding the same closed, said latch resisting the spreading force tending to spread the elevator doors due to the weight of the tubing pressing on the said tapered seat.

12. An elevator for supporting tapered upset tubing, having two doors hinged together and having a tapered seat depressed considerably below the upper face of the elevator for supporting the tapered upset of the tubing, and a latch connecting the two doors for holding the same closed, said latch resisting the spreading force tending to spread the elevator doors due to the weight of the tubing pressing on the said tapered seat, means for pivotally mounting said latch on one of the elevator doors, and a lock associated with the latch for locking it in its latched position, said elevator having a bore above the tapered seat of larger diameter than the pipe supported on the seat.

HERBERT E. GRAU. 30
